(57) **CLAIM**

The ornamental design for a toy, as shown and described.

DESCRIPTION

FIG. 1 is a front, right and top perspective view of a toy, showing my new design;
 FIG. 2 is a rear, left and bottom perspective view thereof;
 FIG. 3 is a front view thereof;
 FIG. 4 is a rear view thereof;
 FIG. 5 is a left side view thereof;
 FIG. 6 is a right side view thereof;
 FIG. 7 is a top plan view thereof;
 FIG. 8 is a bottom plan view thereof;
 FIG. 9 is an enlarged view of portion of FIG. 1 thereof; and,
 FIG. 10 is an enlarged view of portion of FIG. 1 thereof.
 The dot-dash broken lines depict the boundaries of the enlargements that form no part of the claimed design.
